STAR

Eugenio Gatti, Via Piero della Francesca 5, Milan, Italy

Filed Nov. 27, 1959, Ser. No. 58,479

Term of patent 14 years

(Cl. D29—1)

Fig. 1 is an elevational view of one of two like sides of a star, showing my new design.

Fig. 2 is an edge view thereof.

Fig. 3 is a fragmentary elevational view of one of the points of the star viewed along lines 3—3 of Fig. 1.

Figs. 4 and 5 are enlarged cross sectional views taken on lines 4—4 and 5—5 respectively of Fig. 1.

I claim:

The ornamental design for a star, substantially as shown.
